UNITED STATES PATENT OFFICE.

JACOB L. ARMBRUSTER, OF SYRACUSE, NEW YORK.

CHISELING TOOL.

Application filed May 1, 1924. Serial No. 710,331.

This invention relates to chiseling tool adapted to be used more particularly by plumbers for removing lead packings from soil pipe joints.

In the joints of this character, the end of one pipe section is provided with an annular enlargement for receiving the somewhat smaller end of the next adjacent pipe leaving an appreciable annular groove between the adjacent ends of the two pipe sections in which the usual jute packing is first introduced and thoroughly tamped followed by the introduction of molten lead which is also thoroughly tamped to form a gas and liquid-tight joint.

It frequently happens that changes would be made in the soil pipe and fixtures connected thereto necessitating separation of the pipe sections at the joints and therefore, removal of the lead and other packing, and the main object of my present invention is to provide a tool which is better adapted for this particular work than the ordinary cold chisel commonly used.

In the drawings:—

Figure 1 is a perspective view of my improved chisel.

Figure 2 is a perspective view of the adjacent ends of the pipe sections showing the lead packing in the joint and my improved tool in operative position for removing the packing.

One of the pipe sections as —A— is provided at one end with an annular enlargement —a— for receiving the adjacent end of the other section —A'— leaving an annular groove —a'— surrounding the adjacent end of the section —A'— in which is tightly packed a lead filler previously melted and poured into the groove and thoroughly tamped to form a gas and liquid-tight joint.

The tool for removing this lead packing comprises an elongated shank or handle —1— and a chiseled end —2— reduced in thickness and provided with opposite flat faces —3— and —4— thereby forming an offset shoulder —5— on the end of the shank adjacent the blade —2— to limit the entrance of the tool into the work. The side —4— of the blade —2— opposite the shoulder —5— is disposed in substantially the same vertical plane as the corresponding side of the shank —1— while the opposite side

—3— is preferably parallel with the side —4—.

The upper edge as —6— of the blade is straight and is substantially parallel with the axis of the shank —1— while the lower edge as —7— is curved from the shank toward the outer end of the blade to form a cutting edge —8— thereby forming what may be termed a flat tapered blade.

The object in curving the lower edge of the blade —2— is to cause it to deflect the cutting edge —8— upwardly when driven more or less deeply into the lead packing —b— by impact of a hammer or other suitable tool against the outer end of the shank —1— thereby preventing excessive entry of the point of the tool into the work and providing fulcra at different points in its length for prying out the loosened packing.

The lower edge of the offset shoulder —5— constitutes a bearing —9— adapted to fulcrum on the upper face of the flange —a— during the chiseling operation and prying the loosened lead out of the groove —a'—, it being understood that the length of the blade is relatively short as compared with the length of the shank —1—, the outer end of which together with the blade constitutes a hand lever with the shank as the long end or handle thereby affording a relatively long leverage with the shoulder —9— as the fulcrum for prying the chiseled lead loose and if necessary, the outer end of the shank may be forced downwardly during the prying operation by blows of a hammer upon the upper face thereof.

I claim:

A tool for removing lead packing from soil pipe and analogous joints, comprising a steel shank having a transverse shoulder at one end adapted to fulcrum on the flange of the pipe, said shank having an integral blade extending forwardly from and wholly at one side of the shoulder, one edge of the blade being curved longitudinally from the shoulder toward the opposite edge to form therewith a cutting end and also to assist in deflecting the cutting end outwardly as it is driven into the lead packing.

In witness whereof I have hereunto set my hand this 29th day of April, 1924.

JACOB L. ARMBRUSTER.
